(57) **CLAIM**

The ornamental design for a container for a blender, as shown and described.

DESCRIPTION

FIG. 1 is a top, front, right side perspective view of a container for a blender container showing our new design;

FIG. 2 is a bottom, front, right side perspective view thereof;

FIG. 3 is a front elevational view thereof;

FIG. 4 is a rear elevational view thereof;

FIG. 5 is a right side elevational view thereof, the left side being a mirror image of FIG. 5; and,

FIG. 6 is a top plan view thereof.

The bottom of the container for a blender shown in dotted lines is not part of the claimed design.
